UNITED STATES PATENT OFFICE.

GEORGE DE MAZIROFF, OF NEW YORK, N. Y.

MAIL BOX.

Application filed February 14, 1927. Serial No. 168,211.

This invention relates to improvements in mail boxes for use in cities and towns and also relates to improvements in mailing systems including a mail bag in connection 5 with mail boxes and for use by a mail carrier for collecting mail matter from the mail boxes.

One object of my invention is to provide an improved mail box which is provided 10 with a plurality of compartments for the reception of mail matter of different classes such as ordinary letters, special delivery letters, newspapers and the like and which mail box is effective for keeping the different 15 kinds of mail matter separated and thereby avoid entirely or minimize the labor of assorting different classes of mail matter at the post office.

Another object of my invention is to provide 20 means to simultaneously drop all the mail matter of different classes from the mail box to facilitate the collection of the same by the mail carrier.

Another object is to provide a mail bag 25 for use in connection with the mail box to receive the mail matter therefrom and to keep the different classes of mail matter separated just as they were in the mail box.

A further object is to provide an improved 30 mail box which is ornamental in appearance, which is simple in construction, is strong and durable, and which in addition to various compartments for the reception of different classes of mail matter, is 35 also provided with compartments in which may be installed telephones and used as police telephone stations and other compartments in which stamp vending machines may be installed so that the mail box is 40 adapted for use not only for the deposit of mail matter and the keeping of mail matter of different classes assorted, but is also adapted for use as a police telephone station and as a postage stamp vender.

With the above and other objects in view, 45 my invention consists in the construction, combination and arrangement of devices hereinafter described and claimed.

In the accompanying drawings 50 Figure 1 is a front elevation of a letter box and a supporting pedestal or post therefor constructed and arranged in accordance with my invention.

Figure 2 is an end elevation of the same. 55 Figure 3 is a rear elevation of the same. Figure 4 is a vertical longitudinal sec-

tional view of the same, together with the improved mail bag, on a plane intersecting the mail compartments of the mail box and mail bag.

Figure 5 is a vertical transverse sectional view of the same.

Figure 6 is a plan of the mail bag in open position.

Figure 7 is a detail horizontal sectional view, on a somewhat larger scale, of the mail box, on the plane indicated by the line 7-7 of Figure 5, and

Figure 8 is a detail perspective view of the mail bag showing the same in closed 70 position.

My improved mail box 1 may be made of metal or of any other suitable material and is provided with a gable roof or cover 2 which is provided at the sides and also at 75 the ends of the box with projecting protecting eaves 3. The mail box is divided into compartments for the reception of the mail by partitions 4, and the mail receiving compartments may be of any suitable 80 number and of any suitable size. As here shown, a compartment 5 is provided for ordinary letters, a somewhat smaller compartment 6 for special delivery letters, and a compartment 7 for second class mail matter such as newspapers and the like. The front wall of the compartment 5 has a slot 5^a through which letters may be passed by persons mailing them, the compartment 6 has a similar slot 6^a and the compartment 7 has a similar slot 7^a. The said compartments are respectively designated on the front side of the box as "Letter box", "Spec. 85 del.", "Newspaper".

These slots are entirely unobstructed, so 90 that letters and the like may be readily passed therethrough even by a person who has only one hand disengaged, and my mail box facilitates the mailing of letters and the like even under adverse conditions such as 95 during rain or other storms.

The mail compartments are open at the lower side and the bottom of all of said compartments is formed by a single plate or slide 8 which may be drawn outwardly 100 from the front side of the box to drop all the mail matter from all of the compartments simultaneously, as will be understood. The ends of the slide bottom or plate 8 operate in transverse grooves 9 which are formed 105 on the inner side of the end walls 10 of the box and said slide is provided at its rear 110

corners with pivoting outwardly projecting lugs 11 which also operate in said grooves 9, and when the slide has been drawn outwardly sufficiently to entirely open the bottom of all the mail compartments and thereby cause the mail to be dropped from said compartments into the mail bag 12, the said lugs as they reach the front ends of the grooves 9 form pivots which permit the slide bottom to swing downwardly, out of the side, as indicated in dotted lines in Figure 5. The slide bottom is provided at its front side, at a point midway between the ends, with an upstanding arm 13 in which a suitable tumbler lock 14 is mounted. The key 15 of the lock, when inserted therein, operates as a handle whereby to permit the mail carrier to readily operate the slide bottom, to open or close the same. When the slide bottom is in closed position, its front edge and the front side of its arm 13 are flush with the front wall or side of the mail box, as shown in Figure 5, so that said slide does not obstruct the front side of the mail box.

25 The end walls of the mail box are provided at their lower sides with inwardly projecting flanges 16 and grooves 17 above said flanges.

30 The post or pedestal 18 which supports and displays my improved mail box is of ornamental design and the central rear portion of the bottom of the mail box is secured on said post or pedestal as shown in Figure 2, so that the mail portion of the box 35 projects from the post or pedestal outwardly from the post or pedestal and the telephone and stamp vending compartments of the mail box are in the vertical plane of said post or pedestal.

40 In practice and to render the mail box conspicuous so that it can be easily found, the walls or sides of the box are painted yellow and the roof thereof red and the trim and legends of the box are painted black. 45 These colors are to prevail on all of the mail boxes used throughout the cities and towns and on roadways, and hence the finding and use of the mail boxes will be greatly facilitated by such uniform colors and characteristics thereof.

50 It will be understood that persons placing mail matter in the mail box will do so in accordance with the character of the mail matter, that is to say, will place an ordinary letter in the compartment 5, the special delivery letter in the compartment 6, or a newspaper or other article of second class mail matter in the compartment 7 and the mail matter thus separated according to classes in the mail box will be delivered by the carrier in the post office in the bag 12 in which the classes of mail matter will be separated so that the work of assorting the mail in the post office into different classes will be either entirely obviated or very greatly min-

imized, and thus the forwarding of the mail will be greatly facilitated and a very great economy of time and labor will be effected.

55 The telephone compartment is here indicated at 19 and the stamp vending compartment at 20.

60 The bag 12 for use by the mail carrier for collecting the mail from the mail boxes may be made of leather, cloth or any suitable flexible material, is divided by flexible partitions 21 into compartments 5^b, 6^b, 7^b which correspond exactly with the compartments 5, 6 and 7 of the mail box and the mouth of the bag is provided with metal reinforcing frames 22 which frames have end pieces 23 which are pivotally connected together at the medial line of the bag as at 24, said frames also having intermediate arms 25 which are at the upper ends of the partition walls 21 and are also pivotally connected together as at 26, the pivots 26 being coaxial with the pivots 24. The end pieces 23 of the mouth frames are provided with outstanding flanges 27 for engagement with the groove 17 and bear and slide on the flanges 16 of the mail box. When the mail bag has been opened it can hence be readily suspended from and slid to a position below the mail box directly under the mail compartments of the box and the carrier by simply drawing the slide bottom 8 forwardly, after unlocking the same, can cause all the mail matter of various classes in the mail box to drop simultaneously into corresponding classified compartments of the mail bag 100 so that there is no possibility whatever of the various classes of mail matter being mixed as they are dropped from the box into the bag.

105 The bag is here shown as provided with handles 28 on opposite sides of the central portions of the mouth frames. When the mail has been dropped from the box into the bag the carrier then closes the bag and carries it in closed condition either to another 110 box or to the post office. Hence the mail with its various classes separated in the bag, as in the box, is protected fully by the closed mail bag while being carried from one point to another, and all danger of any of the 115 matter being lost by the carrier is obviated.

Having thus described my invention, I claim—

120 1. A mail box open on the lower side and provided with a slide bottom arranged to be drawn outwardly through one side of the box, said box having grooves in opposite walls in which the ends of said slide bottom are mounted and said slide bottom being provided at its rear corners with pivot lugs 125 which also operate in said grooves so that when said slide bottom is drawn outwardly to open the bottom of the box it may be then swung downwardly on said pivots to leave the bottom of the box entirely unobstructed. 130

2. A mail box open on the lower side and provided with a slide bottom arranged to be drawn outwardly through one side of the box, said box having grooves in opposite walls in which the ends of said slide bottom are mounted and said slide bottom being provided at its rear corners with pivot lugs which also operate in said grooves so that when said slide bottom is drawn outwardly 10 to open the bottom of the box it may be then swung downwardly on said pivots to leave the bottom of the box entirely unobstructed, said slide bottom having a lock to secure the same in closed position, said lock having a key which when inserted in the 15 lock forms a handle whereby the slide bottom may be operated.

In witness whereof I affix my signature.

GEORGE DE MAZIROFF.
